UNITED STATES PATENT OFFICE.

CHARLES KALLA, OF CHICAGO, ILLINOIS.

DESIGN FOR A PUZZLE.

44,172.

Specification for Design.

Patented June 10, 1913.

Application filed March 3, 1913. Serial No. 751,932. Term of patent 7 years.

To all whom it may concern:

Be it known that I, CHARLES KALLA, a subject of the Emperor of Austria-Hungary, residing at Chicago, in the county of Cook and State of Illinois, have invented a new, original, and ornamental Design for a Puzzle, of which the following is a specification, reference being had to the accompanying drawing, forming part hereof.

The figure is a top plan view of a puzzle; showing my new design.

I claim:

The ornamental design for a puzzle, as shown.

CHARLES KALLA.

Witnesses:

M. A. MILORD,
G. W. HILTABRAND.
